BEAM HANGER

Joseph R. Mahan, Toledo, Ohio, assignor to The National-Superior Company, Toledo, Ohio, a corporation of Delaware

Application September 20, 1932, Serial No. 633,945
Renewed August 12, 1933

14 Claims. (Cl. 255—18)

My invention relates to beam hangers for suspending well tools and pump rods from walking beams.

It is an object of my invention to provide a beam hanger for a walking beam adapted for ready removal from over a derrick floor or its equivalent, and for readily replacing the hanger in its normal position on a walking beam. Another object is to provide means for safely disconnecting the hanger from the walking beam and for reconnecting the same to the walking beam without requiring the crew to work below the top of the walking beam which is a hazardous position. Another object is to provide a beam hanger which is applicable to different designs of walking beams. Other objects appear hereinafter.

On the accompanying drawing, Fig. 1 is a side elevation of my beam hanger supported on the end of a walking beam; Fig. 2, a plan view of Fig. 1; Fig. 3, a perspective view of one of the clamps or anchor means described herein; Fig. 4, a plan view of one end of the tie-bar 16, a portion being in section; and Fig. 5, a sectional view showing portions of the clamps 9 and 10 in their relation to the walking beam, the section being taken along line 5—5 on Fig. 2.

On the drawing I show one end of a walking beam having the vertical web 1 connecting together the horizontal top flange 2 and the horizontal bottom flange 3. Diagonal braces 4 (only one shown) connect the flanges 2 and 3 together. The apparatus so far described is old.

The end of the beam has the open-ended vertical slot 5 to receive the upper portion of the hanger-bar or suspension member 6 carrying the cross-pin or pivot 7 whose ends are seated in upwardly-open notches 7' in the upper faces of the two blocks 8 which in turn rest on the upper face of the flange 2, one block being at each side of the bar 6 and the slot 5.

9 and 10 are clamp members or anchor means having each a lateral slot 11 to receive the opposite edges of the flange 2, set screws 12 being passed through the lip 13 on the under side of each clamp member and up against the lower face of the flange 2. The opposed lateral faces of the clamp members have the studs 14 which are received into the ends of the hollow T-head 15 forming one end of the upper brace or tie-bar 16. The members 9 and 10 are held from separation or lateral displacement by the stay bolt 17, on which the nuts 18 are screwed up against the outer faces of the members 9 and 10 through which the ends of the bolt project. The upper

walls of the slots 11 are bowed up as at 42 to receive the bolt 17.

The remaining end of the tie-bar 16 is connected to the upper end of the bar 6 by means of a spring-actuated pin 20 carried by the tie-bar 16 and insertable into an opening in the lug or ear 21 on the bar 6. The pin extends out through the casing 22 which contains the helical spring 23 surrounding the portion of the pin within the casing 22 and seated on a shoulder 24 on the pin 20 and bearing against the end wall of the casing. The pin may be retracted against the tension of the spring by pulling the knob 25 formed on the pin away from the outer end of the casing. The length of the bar 16 is adjustable longitudinally by means of the bolts 26 which are passed through selected holes in the overlapping sections 27 and 28 of the bar 16.

29 is a loop-shaped diagonal brace connecting the lower end of the hanger-bar 6 to the clamp members 9 and 10. The lower end of the brace or loop 29 has the horizontal member 30 which is pivoted to the lug or ear 31 on the bar 6. The sides 32 of the loop-shaped brace lie on opposite sides of the walking beam, as shown in Fig. 2, and are connected at their upper or outer ends by the horizontal or cross member 33 which is adapted to lie or be seated in the upwardly-open slots 34 in the clamp or anchor members 9 and 10. The brace 29 is held in the slots 34 by the set screws 35 which pass through the upper lips of the slots 34 and into interlocking contact with the member 33 of the brace 29.

The upper end of the hanger-bar 6 has the eye 36 to receive a hoisting hook. The loop member 29 surrounds the walking beam and is made so that it may be swung upwardly on its pivot 31' in the ear 31 toward the end of the walking beam and past the eye 36 after the spring pin 20 has been withdrawn from the ear 21. A hoisting hook 37 can then lift the hanger-bar and all that is suspended thereon and remove them from over the derrick floor or equivalent so as to afford unobstructed access to whatever is below the described end of the walking beam.

The lower end of the hanger-bar 6 contains the horizontal bearing member 37 from which the usual reins 38 (only one shown) are suspended. The reins are pivotally connected in the usual manner to the pump rod 39 working in the pump barrel 40. The bearing member 37 is substantially in the same horizontal plane as the pivotal support 41 for the walking beam when the latter is horizontal. The bearing member 37 forms the subject matter of my application 110

Serial Number 633,946 filed September 20, 1932.
I claim—

1. In a pumping mechanism, for use with a walking beam to suspend a pump rod therefrom, the combination of a suspension member adapted to be supported at its upper end on the upper surface of the beam, means for connecting the lower end of the suspension member to the pump rod, an anchor means adapted to be adjustably secured to the upper surface of the beam, a brace member attached at one end to the lower portion of the suspension member and detachably connected at its remaining end to the anchor means, and a tie rod connected between the anchor means and the upper end of the suspension member and retaining the upper end of the suspension member in predetermined spaced relation to the anchor means. 80
2. In a pumping mechanism, for use with a walking beam to suspend a pump rod therefrom, the combination of a suspension member adapted to be supported at its upper end on the upper surface of the beam, means for connecting the lower end of the suspension member to the pump rod, an anchor means adapted to be adjustably secured to the upper surface of the beam, a brace member pivotally attached at one end to the lower portion of the suspension member and detachably connected at its remaining end to the upper side of the anchor means, and an adjustable tie rod detachably connected between the anchor means and the upper end of the suspension member and retaining the upper end of the suspension member in predetermined spaced relation with the anchor means whereby, after the brace and tie rods have been detached and the suspension member has been removed, it may be accurately replaced in its former position as soon as the brace member and the tie rod have been attached to the anchor means. 85
3. In a pumping mechanism, for use with a walking beam to suspend a pump rod therefrom, the combination of an anchoring means adapted to be secured to the upper surface of the beam and adjustable lengthwise of the same, suspension means adapted to depend from the upper surface of the beam, means for connecting the lower end of the suspension means to the pump rod, a brace member pivotally attached to the lower end of the suspension means and detachably connected to the upper surface of the anchoring means, and a tie member having its ends connected above the beam to the anchor means and the upper end of the suspension means, one end of the tie member being detachable from one of the two means last mentioned, whereby the suspension means may be removed without changing the position of the anchoring means and whereby when the suspension means and the brace and tie members have been replaced, the original adjustment of the connection between the suspension means and the pump rod is restored. 90
4. In a pumping mechanism, for use with a walking beam having longitudinally lateral flanges at its upper side to suspend a pump rod therefrom, the combination of a pair of opposite clamps adapted to be connected to the flanges of the beam and adjustable longitudinally thereof, there being upwardly-opposite slots in the upper sides of the clamps, a suspension member adapted to be supported on the upper side of one end of the beam, a tie rod above the beam detachably connecting the clamps to the suspension member, a brace member adapted to be looped around the beam, pivoted to the lower end of the suspension member and having the upper end of the looped member seated in the slots, and means releasably locking the said end of the looped member in the slots. 95
5. In a pumping mechanism, for use with a walking beam having longitudinally lateral flanges at its upper side to suspend a pump rod therefrom, the combination of a pair of opposite clamps adapted to be connected to the flanges and adjustable longitudinally thereof, there being upwardly opposite slots in the upper sides of the clamps, a suspension member adapted to be supported on the upper side of one end of the beam, a tie rod above the beam detachably connecting the clamps to the suspension member, a brace member adapted to be looped around the beam, pivoted to the lower end of the suspension member and having the upper end of the looped member seated in the slots, means releasably locking the said end of the looped member in the slots, and means adjustable as to length for connecting the clamps and the upper end of the suspension member. 100
6. In a pumping mechanism, for use with a walking beam having longitudinally lateral flanges at its upper side to suspend a pump rod therefrom, the combination of a pair of opposite clamps adapted to be connected to the flanges and adjustable longitudinally thereof, there being upwardly opposite slots in the upper sides of the clamps, a suspension member adapted to be supported on the upper side of one end of the beam, a tie rod above the beam detachably connecting the clamps to the suspension member, a brace member adapted to be looped around the beam, pivoted to the lower end of the suspension member and having the upper end of the looped member seated in the slots, means releasably locking the said end of the looped member in the slots, and connecting means adjustable as to length between the clamps and the upper end of the suspension member, the connecting means for the clamps and the last named distance and the said locking means all being accessible from the upper side of the beam. 105
7. In a pumping mechanism for use in suspending a pumping rod from a walking beam, the combination of a pump rod-suspension member arranged to be supported from the top surface of said beam, a diagonal brace member hingedly connected at its lower end to the lower end of the suspension member and having its upper end arranged to be detachably supported by the top surface of the beam, and a tie rod disposed between the upper ends of the suspension member and the brace members to hold the same in relative spaced position, said tie rod being detachable, whereby the brace member may be released and swung toward the suspension member to permit the suspension member to be lifted from the beam. 110
8. In a pumping mechanism for use in suspending a pumping rod from a walking beam, the combination of a pump rod-suspension member arranged to be supported from the top surface of said beam, a diagonal brace member hingedly connected at its lower end to the lower end of the suspension member and having its upper end arranged to be detachably supported by the top surface of the beam, and a tie rod disposed between the upper end of the suspension member and the brace members to hold the same in relative spaced position, said tie rod being detachable, whereby the brace member may be released 115

- and swung toward the suspension member to permit the suspension member to be lifted from the beam, the tie rod also being extensible to vary the distance between the upper end of the suspension member and the upper end of the brace whereby the lower end of the suspension member may be adjusted in an arc struck from its point of attachment to the beam. 50
9. In a pumping mechanism for use with a walking beam to suspend a pump rod therefrom, the combination of a suspension member adapted to be supported adjacent its upper end from the beam, means for connecting the lower end of the suspension member to the pump rod, an anchor means arranged to be attached to the beam and to be adjustable along the same, a brace member arranged to be attached to the lower portion of the suspension member and to be detachably connected at its other end to the anchor means, and a tie rod connected between the anchor means and the suspension member retaining the upper end of the latter in predetermined spaced relation to the anchor means. 55
10. In a pumping mechanism, for use with a walking beam to suspend a pump rod therefrom, the combination of a suspension member adapted to be supported adjacent its upper end from the beam, means for connecting the lower end of the suspension member to the pump rod, an anchor means arranged to be attached to the beam and to be adjustable along the same, a brace member arranged to be attached to the lower portion of the suspension member and to be detachably connected at its other end to the anchor means, and a tie rod adjustable as to length and connected between the anchor means and the suspension member retaining the upper end of the latter in predetermined spaced relation to the anchor means. 60
11. In a pump rod suspension mechanism for walking beams, the combination of a suspension member having a hoisting eye and adapted to be supported adjacent its upper end on the upper surface of the walking beam, means for connecting the lower end of the suspension member to the pump rod, an anchor means adapted to be secured to the upper surface of the beam in spaced relation from the suspension member, and a tie-rod pivotally attached at one end to the anchor means and at the other end adjacent to the upper end of the suspension member for retaining the suspension member in predetermined spaced relation to the anchor means when said suspension member may be hoisted from the beam or in operative connection therewith. 65
12. In a pumping mechanism, for use with a walking beam to suspend a pump rod therefrom, the combination of a suspension member adapted to be supported at its upper end on the upper surface of the beam, means for connecting the lower end of the suspension member to the pump rod, an anchor means adapted to be adjustably secured to the upper surface of the beam, a brace member attached at one end to the lower portion of the suspension member and detachably connected at its remaining end to the anchor means, and means connecting the anchor means and the upper end of the suspension member preventing the latter from moving away from the anchor means. 70
13. In a pumping mechanism for use with a walking beam to suspend a pump rod therefrom, the combination of a suspension member adapted to be supported adjacent its upper end from the beam, means for connecting the lower end of the suspension member to the pump rod, an anchor means arranged to be attached to the beam and to be adjustable along the same, a brace member arranged to be attached to the lower portion of the suspension member and to be detachably connected at its other end to the anchor means, and means connecting the anchor means and the suspension member preventing the latter from moving away from the anchor means. 75
14. In a pump rod suspension mechanism for walking beams, the combination of a suspension member having a hoisting eye and adapted to be supported adjacent its upper end on the upper surface of the walking beam, means for connecting the lower end of the suspension member to the pump rod, an anchor means adapted to be secured to the upper surface of the beam in spaced relation from the suspension member, and means connecting the anchor means with the suspension member to prevent the latter from moving away from the anchor means when hoisted from the beam or in operative connection therewith. 80
